UNITED STATES PATENT OFFICE.

LEONARD KEBLER, OF BRONXVILLE, NEW YORK, ASSIGNOR TO WARD LEONARD
ELECTRIC CO., A CORPORATION OF NEW YORK.

RESISTANCE DEVICE.

1,347,102.

Specification of Letters Patent. Patented July 20, 1920.

Application filed October 23, 1915. Serial No. 57,402.

To all whom it may concern:

Be it known that I, LEONARD KEBLER, a citizen of the United States, residing at Bronxville, in the county of Westchester and State of New York, have invented certain new and useful Improvements in Resistance Devices, of which the following is a full, clear, and exact specification.

My invention relates to improvements in resistance devices or rheostats and method of making same, and particularly to that type in which the resistive conductor is embedded or covered by an insulating coating, such as enamel, cement and the like.

In this type of resistance device, there is an insulating base on which the resistive conductor is supported or attached and an adhesive insulating coating is afterward spread over the conductor and support and baked or otherwise caused to solidify so as to firmly hold the conductor in place and protect the conductor from deterioration and from mechanical injury or displacement. In such devices it is necessary to accurately space and position the conductor and terminals to which the conductor may be connected before the first insulating coating is applied. As compactness is desirable, requiring the parts of the resistive conductor to be spaced from adjoining parts by a comparatively short distance, and also to be uniformly spaced, it has previously required considerable time and expense to properly position the conductor and terminals, and to retain the same in position during the application of the insulating coating. The main object of my invention is to provide a construction which will facilitate the application of the resistive conductor to the base in its proper position as well as the terminals and also retain these parts in their proper position during the application of the insulating coating, also provide a form of construction and means which economizes space in positioning the parts, secure a high degree of insulation between the parts and reduce the expense of manufacture. Other objects and advantages of my invention will be understood from the following description and accompanying drawings.

Figure 1 is a plan view of one form of rheostat or resistance device embodying my invention with certain parts removed; Fig.

2 is a plan view of the device complete, and Fig. 3 is a vertical cross section of the base portion on the line 3—3 of Fig. 1.

In the particular embodiment of my invention illustrated in the drawings, there is a base 4 of circular form having suitable supports or extensions 5 for securing the same in position as may be desired, such as to the base of a fan motor. The base may be of porcelain or other suitable insulating material, or in some cases may be in the form of an insulating coating or ground coat applied to a main support of other material. The insulating base or coating has a series of projections 6 extending from the surface of the base and is also shown as having extending from such projections the strips 7 which are shown as substantially parallel to each other forming a series of channels between them. The projections 6 and strips 7 are shown as being of the same material and integral with the base 4, the projections and strips being molded therewith, but in some cases these parts may be of different material from each other and may be fastened together, instead of integral. In some cases the projections 6, or their equivalent, may be of metal and partly bedded in the insulating base or may otherwise be supported therefrom. The channels formed by the strips and projections communicate with adjoining channels around the projections 6. At 8 are shown a number of projections from the base of H form, these projections also being indicated as integral with and of the same material as the base and preferably molded therewith. Over the central cross portion of these projections are located the terminals of the rheostat. These are in the form of metal strips bent around the central part of the projections 8, each terminal having horizontal end portions 10, which are located against the main surface of the base 4, vertical portions 11 extending upwardly along the sides of the central part of the H formed projections, and top portions marked 9 over the central portion of the H formed projections. The terminals are thus bent or looped over the central part of the projections 8, these projections thus holding the terminals in a definite position.

The resistive conductor 12 is shown of zigzag or wave form, one end being elec-

trically connected to the terminal portion 13, the end of the terminal being bent over so as to pinch and firmly secure the end of the resistive conductor. The resistive conductor is shown as extending from the terminal portion 13 through the right hand channel around the lower right hand projection 6, down the next channel and so on, until it finally reaches and is electrically connected to the terminal portion 14 by being pinched under the end of the terminal. The middle terminal is electrically connected to an intermediate portion of the resistive conductor as shown at 15 by a portion of the terminal being bent over to clamp the resistive conductor. The lead wire 16 extends from the terminal portion 13 to the terminal 17, the latter being a screw and nut terminal located at and secured to the side of the base for connection to the external circuit. At one part of the rheostat is a raised part 18 preferably of the same material and molded with the base. This has two perforations 19, 20. On the projection 18 is located a conducting plate 21 which electrically connects the screw and nut terminal 22 with the pivoted rheostat lever 23. The perforation 19 receives the screw 24 at the pivoted end of the lever and the perforation 20 receives the screw of the terminal 22 for holding the parts in place. A wire 25, having its ends bent into and passing through the holes 26 formed in the base, serves as a guard and for holding the lever 23 against the terminals. Around the outer edge of the base are raised portions 27, which with other raised parts form a continuous outer inclosing edge.

The base having been molded in the form and with the projecting portions as above described, the device is assembled by first securing an end of the resistive conductor to an end portion 13 of one of the terminals and the lead 16 connected thereto, and the terminal being bent in proper shape is slipped over the central portion of the right-hand projection 8. The resistive conductor is then fed down through the right-hand channel and bent around the lower right-hand projection 6 and then passed up the next channel and bent around the next projection 6, and so on until at the point where the next terminal is to be connected. The end of the terminal is bent over the resistive conductor so as to firmly clamp it and this terminal is then placed in position upon its projection 8. The resistive conductor is then passed along the succeeding channels and around projections 6 until the end of the resistive conductor is reached, which end is then fastened to the remaining terminal, and the terminal placed in its proper position. In some cases the terminals are first secured to the

resistive conductor at their proper points before starting to apply the parts to the base. With the parts placed in position as described, the heads 6 of the strips serve to definitely position and hold the conductor where the conductor is looped, and the strips 7 serve to prevent the conductor from bending and from moving sidewise out of its proper position. The terminals also are properly positioned by the projections 8 with the end portions of the terminals lying flatwise against the base. The insulating coating 28 is next applied over the resistive conductor and over the flat portions of the terminals which lie against the base, openings between the projections permitting the insulating coating to be applied or flowed evenly over the parts. The resistance device is then baked or otherwise treated so as to solidify the insulating coating which will adhere to the base and hold all parts in a permanently fixed position. In some cases it may be desirable, to apply more than one coating, but by means of my invention I am enabled to secure excellent results by the application of one coating only, because the channels and projecting portions serve to so definitely locate all parts and provide such excellent guides and supports for the insulating coating that the one coating may be evenly and conveniently applied over all parts. The coating will preferably cover the projecting parts 6 and strips 7 so that the exposed surface of the insulating coating will present a comparatively smooth and finished appearance.

After the insulating coating has been baked or caused to set, the lead 16 is secured to the terminal 17, and the lever 23, plate 21 and terminal 22 placed in position, and the guide rod or wire 25 is secured in place. The lever is shown in the off position in Fig. 2; by movement to the right all of the resistance will be included in circuit between the two terminals 17 and 22 by reason of the lever engaging with the left-hand contact surface 9. Further movement to the right will cause the lever to engage the middle contact surface 9, and cut out a portion of the resistance from circuit and further movement to the right-hand position will cause all of the resistance to be cut out of circuit by the contact lever engaging the right-hand contact surface 9. It is apparent that by means of my invention the resistance device or rheostat is very quickly and conveniently manufactured, and that the cost of manufacture is low. The construction also secures compactness, is very durable, and is substantially free from chance of mechanical injury.

In some instances, the base may have the channels only slightly larger than the size

of the resistance conductor and be reflexed so as to definitely position each part of the conductor before the application of the insulating coating. It is apparent that my 5 invention may be embodied in various forms of construction other than that herein particularly shown and described.

Having thus described my invention, what I declare as new and desire to secure by 10 Letters Patent of the United States is:—

1. In a resistance device, an insulating base plate, a resistive conductor on and contacting with said plate, contact terminals on said plate, said plate having projecting portions for positioning said conductor and said terminals, and an insulating coating embedding said conductor and overlying portions of said contact terminals. 15
2. In a resistance device, an insulating base, said base having a plurality of ribs and widened heads at the ends of the ribs, a resistive conductor located on said base between said ribs and passed around and positioned by said heads, and an adhesive insulating coating embedding said conductor. 20
3. In a resistance device, an insulating base, said base having insulating projecting portions extending therefrom, contact terminals positioned by said projecting portions, said terminals having extensions engaging the surface of said base, a resistive conductor connected with said terminals, and an adhesive insulating coating embedding the portions of said terminals which engage the surface of said base. 25
4. In a resistance device, an insulating base, said base having projecting portions, contact terminals of U-shape having end 30 portions engaging the surface of said base, said terminals engaging and positioned by said projections, a resistive conductor, and an insulating adhesive coating embedding

the portions of said terminals engaging the surface of the base and also embedding said 45 conductor.

5. The method of making a resistance device which consists in providing a base portion of insulating material with insulating projections therefrom, placing a resistive 50 conductor in contact with said base portion and between certain of said projections, placing terminals over certain of said projections, and embedding said conductor and portions of said terminals with an insulat- 55 ing adhesive coating.

6. An electrical resistance device comprising a base plate of insulating material having parallel projecting ridges on its under surface forming channels, said ridges 60 having widened heads at alternate ends thereof, a resistive conductor within said channels and in contact with the surface of said plate and extending around said widened heads, and an adhering coating of insulating 65 material covering said conductor and binding all the parts into a solid unitary mass.

7. An electrical resistance device comprising a base plate of insulating material having parallel projecting ridges on its under 70 surface forming channels, said ridges having widened heads at alternate ends thereof, a zig-zag resistive conductor within said channels and in contact with the surface of said plate and alternately in contact with the 75 sides of said ridges and extending around said widened heads, and an adhering coating of insulating material covering said conductor and binding all the parts into a solid unitary mass. 80

In testimony whereof I affix my signature in presence of two witnesses.
